(57) **CLAIM**

The ornamental design for a portable steam generator, as shown and described.

DESCRIPTION

FIG. 1 is a perspective view of the front and one side of a portable steam generator showing my new design;
FIG. 2 is a perspective view of the top, rear and a portion of the bottom thereof; and,
FIG. 3 is a side view of said one side, the opposite side being a mirror image thereof.

The surfaces or portions of the article not shown in the drawing or described in the specification form no part of the claimed design.
